UNITED STATES PATENT OFFICE.

VALENTINE DICKERSON, OF STAPLETON, NEW YORK.

GAME.

1,373,312.

Specification of Letters Patent. Patented Mar. 29, 1921.

Application filed December 31, 1919. Serial No. 348,575.

To all whom it may concern:

Be it known that I, VALENTINE DICKERSON, a citizen of the United States, and a resident of Stapleton, Staten Island, in the 5 county of Richmond and State of New York, have invented a new and useful Game, of which the following is a full, clear, and exact description.

This invention relates to that class of device in which pellets of desired construction are utilized in connection with what might be termed a maze, a central inclosure being associated with such maze, into which the pellets are to be guided by tilting the supporting means for the maze, but without the assistance of the hands in direct contact with the pellets.

It is well known that any number of devices having this construction in mind have 20 been patented and placed upon the market, the best known of which devices being commonly known as "Pigs in clover."

My invention now aims to produce a device having in mind this construction as a 25 basis.

I propose to associate in this connection pellets of peculiar construction, which shall be unique in this particular adaption in that they produce motion when placed upon 30 their surface and are of a highly ludicrous nature.

A further and chief object of my invention is the construction of a maze which shall render it extremely difficult to cause all 35 of the parts employed to move into the central inclosure.

Having these objects in mind reference is had to the attached sheet of drawings in which:

40 Figure 1 is a perspective view of the maze forming the main portion of the game, and,

Fig. 2 is a sectional side view of one of the pellets employed in connection with the maze.

45 In all of these views like reference numerals designate similar parts, and the reference numeral 1 indicates a base which may be of any desired construction or material, and upon the upper face and adjacent and 50 parallel the side edges of the same there is mounted a strip 2, comprising a confining wall.

55 Spaced from the strip 2 and arranged adjacent the corners formed by the same are corner walls 3, having their ends spaced one from the other, so as to provide openings 4

for a purpose hereinafter more fully specified.

Within the space inclosed by the corner strips 3 and spaced from and adjacent the 60 openings 4 are strips such as 5, one of which is provided with inwardly extending strips having their outer ends associated with the edges of the strip 5', and their inner ends terminating at a position short of the point 65 of their intersection, so as to provide a small space between their inner edges.

Arranged upon the base 1, and within the space inclosed by the strip 2 are parts including an incasing member 6, in which 70 there is movably inclosed a weight 7 on the order of a BB shot.

It will now be noted that by virtue of my improved construction of the inclosing members and the parts associated with the base 75 forming the floor of the inclosure, extreme difficulty will be experienced in causing the pellets to move extraneous of any hand guidance into the inclosure formed by the strip 5' with which the inwardly extending 80 strips are associated. This difficulty may well be appreciated upon noting that a pellet entering through the opening 4 between the corner strips 3 is confronted with the obstacle of the strips 5. The pellet must 85 now be worked between these latter strips, and upon passing between them must enter into the inclosure formed by the strips 5, and inwardly extending strips 5'. Even upon one or two pellets entering into this inclosure 90 it is extremely difficult to cause a third pellet to move into the same by virtue of the fact that upon the base 1 being tilted in a certain direction the pellets already within the inclosure will be caused to move from the 95 same.

Further, by virtue of the peculiar construction of the pellets the same will be caused to perform any number of amusing antics upon reaching the inclosure afore 100 described, so that a great amount of mirth is provided and amusement afforded to the person operating the game as well as to on-lookers.

Obviously numerous modifications of 105 structure might well be resorted to within the scope of my invention, which I claim as:

1. A game, including a base, corner walls mounted upon said base and having their end edges spaced one from the other, whereby 110 to provide a plurality of openings, strips also secured to said base, and being arranged

- within the space inclosed by said corner strips, and in a position at which they are in line with and spaced from the openings existent between said corner strips, means attached to one of said latter strips for forming an inclosure, said base being adapted to receive a movable means adapted to be embodied within said inclosure by rocking said base.
- 10 2. A game, including a base, corner walls mounted upon said base and having their end edges spaced one from the other, whereby to provide a plurality of openings, strips

also secured to said base, and being arranged within the space inclosed by said corner strips, and in a position at which they are in line with and spaced from the openings existent between said corner strips, inwardly extending strips having one of their ends attached to one of the first named strips, 15 their opposite ends being spaced from each other, whereby to form an inclosure, said base being adapted to receive movable means to be moved into said inclosure by rocking said base.

VALENTINE DICKERSON.
